MANICURING DEVICE

Ethel A. H. Toreson, Minneapolis, Minn.

Substituted for application Serial No. 672,491,
May 27, 1946. This application December 20,
1948, Serial No. 66,357

1 Claim. (Cl. 132-73)

1

This invention appertains to novel and useful improvements in manicuring devices and is a substitute application for my application entitled "Manicuring device," Serial No. 672,491, which was filed on May 27, 1946.

The primary object of the present invention is to retain the wrist of an individual as well as the hand including the fingers immobilized for manicuring the finger nails of the individual in a manner which is safe for the individual and which avoids much discomfort to the person performing the manicuring operations.

Another object of this invention is to retain all of the joints, the knuckles and the wrist of an individual's hand so that substantial movement is avoided and prohibited and also to retain the fingers so that the finger tips are spaced from each other for maximum freedom from interference by the next adjacent finger or fingers when cutting the finger nails of a person.

Ancillary objects and features of novelty, such as simplicity of structure, will become apparent to those skilled in the art, in following the description of the preferred form of the invention, illustrated in the accompanying drawings, wherein:

Figure 1 is a plan view of the back of the device showing the same applied to the hand, and

Figure 2 is a sectional view taken substantially on the line 2-2 of Figure 1 and in the direction of the arrows, the hand being removed from the device.

There is provided a device which is made up of plastic or other suitable rigid material having complementary front and rear sections or halves 10 and 11, respectively, so shaped to conform to the front and back portions of a hand and wrist of an individual.

Finger stalls 12 extend from the sections 10 and 11, forming finger accommodating members, and they are spread apart in divergent fashion. The finger stalls are of such length to fit the average child's hand whereby the joints and knuckles are encased but the finger tips and finger nails are exposed. For this construction, it is necessary that the ends of the tubular stalls be cut off or truncated as shown in Figure 1 so that the tips of the fingers 13 will project through the openings, exposing the finger nails 14.

The two sections 10 and 11 are hinged together along one edge 15, as by means of conventional hinges 16, and the sections open apart in the expected manner at their opposite edges 17, which edges are adapted to be normally locked together to hold the sections closed. Any suitable means

2

may be used in closing or latching the sections together. However, it has been found preferable and desirable to utilize spring clips or catches 18 attached to the section 11 and adapted to hook over projections or pins 19 on the section 10. By releasing the clips 18, the sections 10 and 11 may be swung apart and the hand placed in the device, after which, as the sections are closed and fastened, the hand will be held with the fingers rigidly extended and spread apart so that the finger nails are in maximum comfortable spaced relation. Hence, the nails can readily be trimmed or similar work be performed thereon as required and desired.

15 The wrist portion 20 of the device is of such length as to pass beyond the wrist joint, as indicated at 21, and thus act as a rigid cuff to prevent the hand bending at the wrist. Thus, the hand and fingers will be held in such manner that a 20 child's nails may be trimmed without the usual bothersome and sometimes dangerous movements which make this work difficult.

The wrist receiving portion 20 is substantially elliptical in cross-section, since the normal wrist 25 of an individual is of that shape.

In use of the device, the wrist of a person is disposed between the sections and retained thereby. The hand-receiving portion which is fixed to the wrist-receiving portion accommodates the 30 actual hand of the individual. The finger stalls accommodate the fingers, maintaining them in divergent relation with respect to each other and all of the knuckles and joints are rendered immobile. Hence, it is only necessary to grasp the 35 entire device and cut the person's finger nails without interference with or from the next adjacent fingers or nails.

It is apparent that certain variations may be made without departing from the spirit of the 40 invention.

Having described the invention, what is claimed as new is:

A device for use on a person's hand and wrist to prevent substantial movement of the wrist and 45 of all knuckles and joints comprising a pair of sections of rigid material, one of said sections formed in conformity with the top of a person's wrist, fingers and hand, and the other section formed in conformity with the bottom of the 50 wrist, fingers and hand, means disposed at one corresponding side of each of said sections hingedly connecting said sections together and a latch means carried by the opposite sides of said sections, each pair of finger conforming portions 55 diverging from the other pairs, and said finger

conforming portions being truncated to thereby expose the fingernails of the wearer of the device.

ETHEL A. H. TORESON.
